(57) **CLAIM**

The ornamental design for a golf club head cover, as shown and described.

DESCRIPTION

FIG. 1 is a perspective front view of a golf club head cover; FIG. 2 is a front view of the golf club head cover of FIG. 1; FIG. 3 is a rear view of the golf club head cover of FIG. 1; FIG. 4 is a side view of the golf club head cover of FIG. 1; FIG. 5 is a top view of the golf club head cover of FIG. 1; and, FIG. 6 is a bottom view of the golf club head cover of FIG. 1. The darker broken lines on the top, front and rear portions of the golf club head cover represents conventional stitching. All other broken lines represent key loops that form no part of the claim.
